UNITED STATES PATENT OFFICE.

FRANK UMBRIACO, OF NEW YORK, N. Y.

ACCORDION-LOCKING MEANS.

Application filed March 8, 1927. Serial No. 173,658.

This invention relates to improvements in accordion bellows locking means and has for one of its objects the provision of locking means for accordions adapted when in unlocked position to be substantially slid out of sight and frictionally maintained in said position.

Another object of the invention is to provide an accordion with locking means on both sides thereof, the said locking means being adapted to be sprung out of locking position and slid into a casing and frictionally maintained in said position.

A further object of the invention is to provide an accordion with locking means comprising a plurality of spring plates in engagement with headed screws or studs when in locking position, and the said plates being adapted to be sprung out of engagement with the said studs and slid into an opening formed on each side of the accordion by the usual hand strap and the walls of the accordion casing.

Other objects and novel features of construction will become apparent as the specification proceeds.

Referring to the drawings forming a part of this specification:

Figure 1 is a front view mostly diagrammatic, of an accordion embodying my invention.

Figure 2 is a fragmental end view of same looking from the right of Fig. 1 and

Figures 3 and 4 are detail views in perspective of the locking plate and guide plate respectively.

Referring to the drawings in detail, 5 indicates an accordion, comprising an upper section 6 and a lower section 7 joined by the usual bellows 8. A hand strap 9 is secured to the lower section 7 in such manner as to provide spaces 10 on both sides of the said section 7 the object of which will presently be described.

To lock the bellows when the accordion is not in use, I provide locking means comprising resilient plates 11 preferably made of spring steel, slidably guided in a channel 12 cut in guide plates 13 secured to each side of the lower section 7 near the juncture thereof with the bellows 8. Headed screws or studs 14 in the upper section 6 pass through openings 15 in the plates 11 and

maintain the said plates in locking position. 55

To unlock the bellows, the plates 11 are sprung outwardly by pulling upon studs or knobs 16 secured to the upper portion of the plates 11, until the openings 15 which are approximately the size of the heads of the 60 studs 14 are disengaged from the said studs and the bolts are then slid downwardly into the spaces 10 where they are maintained and frictionally held by projections 17 at the lower end of the plates 11 bearing 65 against the strap 9. These projections 17 also form a stop for limiting the upward movement of the plates 11. While I have described the strap 9 as forming a casing for the plates when they are slid down out of 70 locking position, I desire it understood that independent casings may be used if desired.

From the foregoing it will be seen that instead of the old unsightly manner of locking 75 the bellows which usually consisted of a strap permanently fastened to one section of the accordion and releasably secured to the other section for unlocking, which would leave the said locking strap dangling when so unlocked, I have provided locking means that may readily be sprung out of position and slid into a casing where it is maintained until it is again withdrawn for locking. I desire it understood that I do not limit 80 myself to the exact construction disclosed and described as many variations or changes of my invention may be made without departing from the scope of the appended 85 claims. 90

Having described my invention what I claim as new and desire to secure by Letters Patent is:

1. In an accordion provided with bellows intermediate its sections, a guide plate provided with a slot therein secured to one of the sections, a movable locking plate passing through the said slot and provided with an opening near one end thereof, a stud in the other section passing through the said opening for releasably maintaining the locking-plate in locking position therewith and a stop on the locking-plate to limit the movement thereof in locking direction. 95

2. In an accordion provided with bellows 100 intermediate its sections, a guide plate pro-

vided with a slot therein secured to one of the sections, a stud in the other section, a resilient slidable member passing through the slot in the guide plate in locking engagement with the stud and adapted to be sprung out of locking engagement therewith, a stop at the bottom of the slidable member in engagement with the guide plate to limit the

upward movement thereof in locking direction, and a casing on the guide plate holding section adapted to receive and frictionally maintain the slidable member when slid into unlocking position. 10

In testimony whereof I hereunto affix my signature.

FRANK UMBRIACO.
